PENCIL HOLDER

Arthur Henry Ehler, Devils Tower, Wyo.

Application December 20, 1938, Serial No. 246,897

1 Claim. (Cl. 120—6)

This invention aims to provide a novel combination article, embodying an envelope sealer, an ink eraser and a lead pencil eraser, the parts specified cooperating in a novel manner. Another object of the invention is to supply a device of the class described, which may be carried on a pencil, or be used detached from a pencil, or be employed as a fixed article on a desk.

10 It is within the province of the disclosure to improve generally and to enhance the utility of devices of that type to which the present invention appertains.

With the above and other objects in view, 15 which will appear as the description proceeds, the invention resides in the combination and arrangement of parts and in the details of construction hereinafter described and claimed, it being understood that changes in the precise 20 embodiment of the invention herein disclosed, may be made within the scope of what is claimed, without departing from the spirit of the invention.

In the accompanying drawings:

25 Fig. 1 shows in elevation, a device constructed in accordance with the invention;

Fig. 2 is a longitudinal section of the article shown in Fig. 1;

30 Fig. 3 is an elevation showing a modification; Fig. 4 is a vertical section of the article shown in Fig. 3;

Fig. 5 is an elevation showing a further modification;

35 Fig. 6 is a vertical section of the article depicted in Fig. 5;

Fig. 7 is an elevation showing another modification;

Fig. 8 is a longitudinal section of the device delineated in Fig. 7.

40 In carrying out the invention, as disclosed in Figs. 1 and 2, there is supplied a body 1, made of any desired material, and of approximately frusto-conical form. In the wider end of the body 1 there is a recess 2, about which the body

45 1 extends, saving where the recess opens through the wider end of the body. The inner portion of the recess 2 is curved, as shown in Fig. 2, to conform to the periphery of a roller 3, which is used in sealing envelopes. The roller 3 projects a little beyond the wider end of the body.

50 The roller 3 is journaled for rotation on a solid shaft 4, extended through the body 1, transversely, and transversely across the recess 2. A nut 5 is threaded on one end of the shaft 4 and 55 engages the body 1, at one side thereof. The

shaft 4 has a fixed collar 6, engaging the opposite side of the body, the body being bound firmly between the collar 6 and the nut 5.

The shaft 4 projects beyond the collar 6 to form a tip 7, on which is detachably mounted a 5 lead pencil eraser 8, arranged at right angles to the longitudinal axis of the body 1.

A bore 9 is formed in the longitudinal axis of the body 1 and extends inwardly from the smaller end of the body. The numeral 10 designates a 10 sharpened and pointed ink eraser, made of metal the eraser including a head 11 received in the bore 9, the head defining a shoulder 12, which abuts against the smaller end of the body 1, the head being held frictionally in the bore 9. The 15 head 11 is provided with a circumscribing groove 14, adapted to receive a finger 15, slideable in the body 1, and attached to one end of a spring latch 16, secured at one end to the body 1. The purpose of the latch 16 and the finger 15 is to hold 20 the ink eraser 10 detachably assembled with the body 1. In order that the article can be carried conveniently in the pocket, a spring pocket grip 18 is secured at one end to the body 1, the grip 25 extending toward the smaller end of the body.

It will be seen that the article includes, in convenient relation to each other, the envelope sealing roller 3, the lead pencil eraser 8, and the ink eraser 10. The article can be used in a variety of ways. For instance, when all parts are assembled, as shown in Fig. 2, the article can be carried in the pocket. If the operator wishes, he can free the latch 16 from the head 11 of the ink eraser 10, the ink eraser being removed. Then, 30 one end of a lead pencil (not shown) may be inserted into the bore 9, the article being pencil-carried.

Some persons may not wish to carry the article either in the pocket or on a lead pencil, but may wish to mount it fixedly on a desk, as shown 40 in Fig. 1. Under such circumstances, a narrow slit 19, shaped to receive the ink eraser 10 closely, may be formed in the horizontal part of a desk 20, the pencil eraser 8 being compressed against the vertical part of the desk and aiding in holding the body 1 in the upright position of Fig. 1. Since the lead pencil eraser 8, made of rubber or similar material, is compressed, the eraser has 45 a frictional hold on the vertical part of the desk 20, and will aid in preventing the ink eraser 10 from being detached from the groove 19 in the desk.

In Figs. 3 and 4, parts hereinbefore described have been designated by numerals already used, with the suffix "a". In this form of the inven- 55

tion, a recess **2a** extends entirely through the body **1a**, transversely of the longitudinal axis of the body. The pocket grip **18a** extends toward the wider end of the body, and is located near the narrower end of the body.

5 In Figs. 5 and 6, the latch **16** and the corresponding parts of Fig. 2 are omitted. The head **11b** of the ink eraser **10b** is threaded at **21** into the bore **9b**.

10 The axis of the recess **2b** extends longitudinally of the body **1b**, rather than transversely thereof as in Fig. 2. The upper end of the body **1b** is reduced, as shown at **22**, and exposes opposed portions of the roller **3b**. The roller **3b** is journaled on a tubular shaft **4b**, having its inner end threaded at **23** into the bore **9b**. The shaft **4b** is supplied with an outstanding shoulder **24**, engaging the wider end of the body **1b**.

15 A second lead pencil eraser **50** is mounted on the tip **7b** of the shaft **4b**.

In Figs. 7 and 8, the recess **2c** opens through one side only of the body **1c**, to expose the roller **3c**. A second pencil eraser **50c** is mounted on the **5** smaller end of the body **1c**.

What is claimed is:

In an article of the class described, a body provided at its lower end with an anchor member shaped to be received in the horizontal part of **10** a desk, the body being provided at its side with a lateral resilient member, compressible against a vertical part of a desk to hold the anchor member assembled with the horizontal part of a desk, and a sealing member mounted on the **15** body.

ARTHUR HENRY EHLERT.
